PIANO CASE

Winsor D. White, Jr., Blowing Rock, N.C., assignor to D. H. Baldwin Company, Cincinnati, Ohio, a corporation of Ohio

Filed Nov. 17, 1966, Ser. No. 4,714

Term of patent 14 years

(Cl. D56—9)

The figure is a perspective view of a piano case embodying my new design.

The dominant features of my design reside in the portions shown in solid lines in the drawings, the conventional keyboard being shown in broken lines. The side of the piano not shown is the same as the side shown.

I claim:

The ornamental design for a piano case, substantially as shown and described.
